4 Claims. (Cl. 250—153)

The invention relates to television transmission tubes of the charge storage type, and particularly to tubes in which an electron stream is controlled by charges applied to a charge storage electrode.

A tube of this type contains for instance a foraminous gridlike charge storage electrode carrying a mosaic of insulated photoelectric particles. This mosaic electrode is illuminated by the light of the television image so that the insulated particles acquire a positive charge. An additional source of electrons is arranged within the tube in such a manner that these electrons are directed in their movement towards the gridlike electrodes. These electrons liberate upon the grid a number of secondary electrons of slow velocity and the passage of these slow electrons through the grid is controlled by the charged particles upon the grid.

The known tubes of this type have however a drawback which decreases their sensitivity. The experiments show namely that not only the slow electrons which are easily influenced by the charges upon the mosaic are moving through the grid openings but that also fast primary electrons pass through the control grid and produce an unmodulated current at the signal electrode, which may be a multiple of the modulated image current. This unmodulated current is particularly large in case the secondary electrons are emitted by the backside of the charge storage electrode which is not illuminated by the light of the image and is not photo-sensitive. In this case a large number of primary electrons will flow through the openings of the gridlike electrode and will arrive upon the signal electrode of the tube.

It has been suggested to make the signal electrode cylindrical so that the cylinder is situated around the stream of electrons passing through the grid. With a suitable potential at the signal electrode, the slow controlled electrons shall be guided towards and collected by the signal electrode whereas the fast primary electrons move in axial direction and are collected by an electrode arranged vertically to the axis of the tube. In this manner it may be possible to collect the primary electrons but these electrons produce again secondary electrons at the collecting electrode and new disturbances are produced.

It is an object of the present invention to provide an electrode arrangement in which only the secondary electrons emitted by the charge storage electrode and controlled by the potentials

of this electrode are collected by the output electrode.

It is a further object to provide a television transmission tube of high sensitivity and low unmodulated current. A further object is to separate the modulated electrons from the unmodulated electrons by a simple electrode arrangement.

According to the invention an electrode is arranged between the collecting electrode for the primary electrons and the signal electrode and this additional electrode has a negative potential against the collecting electrode.

Other aspects of my invention will be apparent or will be specifically pointed out in the description forming a part of this specification, but I do not limit myself to the embodiment of the invention herein described, as various forms may be adopted within the scope of the claims.

Referring to the drawing the figure shows a longitudinal section through a tube according to the invention.

The tube 1 is an evacuated envelope having a plane window 2 at one end thereof. A transparent metal layer is applied to the inside of this window. Instead thereof a wire screen 3 may be arranged as collecting electrode near the window. The other end of the tube contains an electron gun system 8, and a concentrating electrode

9. At this end of the tube, there are also provided a pair of deflecting coils 10, as shown. A mosaic electrode 4 is arranged in the path of the cathode ray produced by the electron gun system. This mosaic electrode is permeable to electrons and has for instance the form of a screen or of a perforated foil. The side of the grid towards the window is covered with a large number of insulated photoelectric particles. The mosaic electrode has a clean metal surface at the other side

thereof and this surface may be made secondary emissive by applying suitable and known substances to these surfaces for instance caesium and caesium oxide. A cylindrical signal electrode 5 is arranged along the wall of the tube on the side of the mosaic towards the window. This signal electrode collects the controlled electrons. A decelerating electrode 6 is arranged between electrode 5 and the metal layer 3. This electrode has according to the invention the property that it suppresses the passage of secondary electrons emitted by the metal layer 3 towards the signal electrode. The signal electrode 5 has a potential which is approximately 20 volts positive against mosaic electrode 4. The metal layer 3 has a potential of approximately —10 volts against the

55

mosaic electrode and the decelerating cylinder 6 a potential of -30 volts against the mosaic electrode.

If an optical image is thrown by means of a lens 7 through the metal screen 3 upon the mosaic electrode 4 the mosaic layer assumes a charge distribution corresponding to the optical image. If the rear side of the mosaic electrode 4 is scanned by a cathode ray the primary electrons of the ray will liberate secondary electrons and these slow secondary electrons are drawn through the openings of the mosaic electrode by the positive charges of the mosaic layer. In the space adjacent to the mosaic the electrode 4 has the highest positive potential. The slow electrons moving through the openings of the mosaic electrode are completely taken up by the signal electrode 5. The primary electrons moving into this space through the openings of the mosaic electrode pass through the space surrounded by electrode 5 and impact upon the metal screen 3 in consequence of their high initial velocity. The secondary electrons emitted by the screen 3 can however not move towards electrode 5 on account of the decelerating field of electrode 6 having a potential which is 20 volts lower than that of metal screen 3, so that all secondary electrons emitted by this layer fall back upon the plane of their origin. It is therefore completely avoided that primary electrons or electrons produced by the primary electrons reach the signal electrode. This has the advantage that the shot noise of the signals derived from electrode 5 is very low because the signal current has a very low D. C. component.

The invention is not limited to the embodiment represented in the figure. It is not necessary that electrode 5 has the form of a homogeneous metal cylinder. It may for instance have the form of a grid or netting and may be arranged as the first grid of a secondary emission multiplier arranged behind said grid.

What I claim is:

1. A television picture signal generating tube comprising an apertured charge storage electrode having photosensitive particles deposited thereon and adapted to have an optical image focused thereon, an electron gun at one side of said electrode for directing a beam of electrons thereat to produce secondary electrons upon impact therewith, an output electrode adjacent the other side of said storage electrode for receiving the secondary electrons passing through the apertures thereof, a collecting electrode also at the other side of said storage electrode for intercepting the primary electrons of said beam passing through said apertures of said storage electrode, and a decelerating electrode adjacent said collecting electrode for retarding secondary electrons produced by electron impact with said collecting electrode thereby to prevent said last-named secondary electrons from reaching said output electrode.

2. A television picture signal generating tube

comprising an apertured charge storage electrode having photosensitive particles deposited thereon and adapted to have an optical image focused thereon, an electron gun at one side of said electrode for directing a beam of electrons thereat to produce secondary electrons upon impact therewith, a cylindrical output electrode adjacent the other side of said storage electrode for receiving the secondary electrons passing through the apertures thereof, a collecting electrode also at the other side of said storage electrode for intercepting the primary electrons of said beam passing through said apertures of said storage electrode, and a decelerating electrode disposed between said output electrode and said collecting electrode for retarding secondary electrons produced by electron impact with said collecting electrode thereby to prevent said last-named secondary electrons from reaching said output electrode.

3. A television picture signal generating tube comprising an apertured charge storage electrode having photosensitive particles deposited thereon and adapted to have an optical image focused thereon, an electron gun at one side of said electrode for directing a beam of electrons thereat to produce secondary electrons upon impact therewith, an output electrode adjacent the other side of said storage electrode for receiving the secondary electrons passing through the apertures thereof, a transparent collecting electrode disposed in the path of the light of said image and also at the other side of said storage electrode for intercepting the primary electrons of said beam passing through said apertures of said storage electrode, and a decelerating electrode adjacent said collecting electrode for retarding secondary electrons produced by electron impact with said collecting electrode thereby to prevent said last-named secondary electrons from reaching said output electrode.

4. A television picture signal generating tube comprising an apertured charge storage electrode having photosensitive particles deposited thereon and adapted to have an optical image focused thereon, an electron gun at one side of said electrode for directing a beam of electrons thereat to produce secondary electrons upon impact therewith, a cylindrical output electrode at the other side of said storage electrode for receiving the secondary electrons passing through the apertures thereof, a transparent collecting electrode in the path of the light of said image and also at the other side of said storage electrode for intercepting the primary electrons of said beam passing through said apertures of said storage electrode, and a cylindrical decelerating electrode adjacent said collecting electrode for retarding secondary electrons produced by electron impact with said collecting electrode thereby to prevent said last-named secondary electrons from reaching said output electrode, said electron gun, said collecting electrode and said decelerating electrode being mounted on the same axis.

WERNER FLECHSIG.
